UNITED STATES PATENT OFFICE.

CHARLES J. VAN DEPOELE, OF LYNN, MASSACHUSETTS.

ELECTRIC LOCOMOTIVE.

SPECIFICATION forming part of Letters Patent No. 448,562, dated March 17, 1891.

Application filed May 26, 1890. Serial No. 353,246. (No model.)

To all whom it may concern:

Be it known that I, CHARLES J. VAN DEPOELE, a citizen of the United States, residing at Lynn, in the county of Essex and State 5 of Massachusetts, have invented certain new and useful Improvements in Electric Locomotives, of which the following is a description, reference being had to the accompanying drawings, and to the letters of reference 10 marked thereon.

My invention relates to improvements in electric locomotives, and more particularly to an electric propelling mechanism in which the motor is mounted upon and wholly sustained by the axles of the truck carrying the vehicle, so as to form a part of the construction thereof independent of the springs or mechanism supporting the car-body.

Many electric-railway cars are at present 20 operated by a pair of motors, each sleeved on one of the axles of the carrying-wheels, their free ends being sustained by spring-connections and their armature-shafts connected by double gearing with their respective 25 axles. According to the present invention but a single motor is employed, and said motor is sustained at its opposite ends upon both the axles of the truck with its armature-shaft connected by gearing and imparting power 30 to both of the said axles. Ample provision is made for the necessary independent movement of each axle—as, for instance, in passing over uneven portions of track; and a particular feature of the invention relates 35 to the means which I have provided for permitting independent adjustment of said axles to the inequalities of the roadway without pinching, binding, or destroying the gears connecting the armature-shaft and the axles. 40 The motor itself is flexibly sustained, so that it will not be injured by excessive jarring, and the gears between the armature-shaft and the axles are also flexible, in order to prevent injury to the teeth of the pinion under sudden or excessive strain. Furthermore, the parts of the motor are detachable 45 and are easily removed and replaced.

The details of construction and arrangement will be fully hereinafter set forth and 50 referred to in the appended claims.

In the drawings, Figure 1 is a view in elevation showing a motor embodying the inven-

tion, two of the carrying-wheels in rear thereof with their axles in section. Fig. 2 is a view in elevation showing a truck adapted for use 55 in connection with my improved motor, the motor being indicated in dotted lines. Fig. 3 is a side elevation, partly in section, showing the motor with parts removed for better illustration. Fig. 4 is a top plan view of a 60 motor, the gearing, and the wheels and axles of a car-truck. Fig. 5 is a side elevation showing the wheels of a truck with the gearing and armature-pinion. Fig. 6 is a top plan view of the wheels and gearing shown in 65 Fig. 5. Fig. 7 is a detail elevation of one of the armature-pinions. Fig. 7^a is a detail section of one of the armature-pinions. Fig. 8 is a detail section of one of the gear-wheels.

In the drawings, A B represent pairs of carrying-wheels provided with axles a b. The carrying-wheels are connected to form a truck by a suitable frame C C', substantially as indicated in Fig. 2, the load to be carried being sustained upon the frame. The propelling-motor D extends between and is supported at its opposite extremities by the axles a b, its armature-shaft being parallel with and centrally located between the axles to be driven. The general form of the motor comprises two 80 horseshoe field-magnets E F, provided at their extremities with magnetizing-coils e e' f f'. The distance between the extremities of the field-magnet coils is bridged by pole-pieces G G', and between the pole-pieces is rotatably 85 mounted the armature H, the shaft h of which is sustained by diamagnetic yoke-plates g g', carrying suitable bearings and secured to the pole-pieces G G'. The pole-pieces E F of the horseshoe field-magnets are divisible along 90 the central line, and are provided with lugs e² e³ f² f³, by which they are mechanically connected, and said field-magnets straddle the axles a b, upon which, being divisible, they are readily placed in position. The central 95 portions of the field-magnet system—that is to say, the pole-pieces G G' and the end portions thereof, upon which the magnetizing-coils e e' f f' are placed—are preferably made of the softest iron and united to the heel-pieces E F by suitable bolts d. The structure so formed possesses great mechanical strength, and is at the same time so completely detachable that any part thereof may 100

be removed or replaced without necessarily taking down the whole machine. The space between the legs of the field-magnets should be somewhat larger than the diameter of the axles $a b$, so as not to interfere with or prevent independent motion of the axles or movement of the latter with respect to said axles. The motor is sustained in operative position by spring-boxes $I I' J J'$, placed upon the axles at each side of each end of the motor, as indicated in Fig. 4. Each box comprises a bearing-block $i j$, capable of vertical motion within said box, and the blocks are normally held in central position by supporting-springs $i' i^2 j' j^2$. The boxes are connected to plates $I^2 J^2$, which fit against the side faces of the heel-pieces of the field-magnets $E F$ of the motor, and being securely bolted thereto mechanically connect the motor with the spring-boxes, so that the entire weight of the motor is sustained thereon at each side of each end. Top and bottom springs being provided in each box, the motor will be carried between the four sets of supporting-springs. It will furthermore be understood that the space existing between the legs of the field-magnets and the axles, taken in connection with the range of the supporting-springs, will permit the motor to move up or down and the axles $a b$ to have their usual freedom of independent twisting movement without injuriously affecting the position of the motor.

The armature-shaft of the motor carries a pinion K , which at its opposite sides meshes with gear-wheels $L M$ upon the axles $a b$, and I prefer to provide gearing at but one end of the armature-shaft, thereby minimizing the difficulty of transmitting power through a train of gearing the alignment of which is frequently destroyed. The gears $L M$ do not change their position at right angles with the axles $a b$; but in order to provide sufficient elasticity to prevent stripping or breaking any of the gear-teeth when the motor is suddenly started or stopped, or is subjected to any violent concussion or jar, I provide a flexible part between the peripheries of said gear-wheels and the axle. As here shown, each of said wheels comprises a hub N , rigidly geared to the axle and having a number of peripheral recesses n , four being here shown. The periphery O of the wheel is provided with the teeth O' to engage the pinion K . This part of the wheel is formed of a rim having a web extending from one side thereof, to the hub upon which the said web is rotatably mounted. The under side of the rim O is also formed with a number of recesses n' , the same corresponding with the recesses in the hub N , and the hub and rim are then connected by strong leaf-springs P , fitting into the recesses of the hub and of the rim. The springs are secured in the recesses n by suitable bolts p passing therethrough, but are left free at their ends in the recesses n' . The inner side of the wheel is closed up flush with the outer edge of the rim by a suitable plate Q , secured

thereto. Obviously a heavy pull upon the rim of a wheel constructed as just described would bring the springs P into action and permit a false motion of the rim upon said springs depending upon their strength for its extent. The gears just referred to as having flexible parts between their hubs and their peripheries are designated, and will be hereinafter referred to, as "dynamometric gears." The motor being mounted so as to be movable up and down between supporting-springs, the position of the pinion K will vary to some extent between the gear-wheels $L M$, but not sufficiently to disengage the same therefrom in view of their flexible construction, as their peripheries will yield to compensate the vertical movements of the pinion. This, however, while overcoming one prominent difficulty, will not be sufficient to secure the continuous operation of the machine, since whenever the truck is upon a track not perfectly level the gears $L M$ will be out of alignment. I therefore provide a specially-constructed pinion K , which will permit of some movement of its own parts and distortion of the pitch-line of its teeth, thus accommodating itself to the varying positions of the gear-wheels with which it is in mesh.

The pinion K is composed of any desired number of metal disks k , clamped together and formed with peripheral teeth. The said pinion is geared onto the armature-shaft h ; but the connections between the plates, as also the connection between the pinion and the shaft, are sufficiently loose to permit the said plates to move slightly with respect to each other to produce the distortion or false movement necessary to maintain an operative connection between said pinion and the gears $L M$ under all conditions.

Fig. 8 is a detail view of the pinion.

With the described construction, which may of course be modified in various minor respects without departing from the invention, an extremely strong and simple motor mechanism is provided. By the use of the dynamometric gear and a flexible pinion the necessary elasticity is secured, and counter-shafts or intermediate gearing are entirely dispensed with without interfering with the free movement of the separate axles of the truck. The elongated form of motor is also advantageous, in that it permits the placing of a very powerful machine in a very small space, and, moreover, distributes the weight equally upon all the wheels to be driven. Furthermore, the supports for the motor being sleeved upon the axles outside of the motor structure and secured laterally thereto, it will be apparent that either the entire or a part of the upper or lower portion of the motor may be removed without displacing the remainder by merely removing the proper side bolts, then disconnecting the ends of the field-magnets, and removing the desired part, the boxes remaining in position upon the axles and sustaining the remaining parts.

Having described my invention, what I claim, and desire to secure by Letters Patent, is—

1. An electric locomotive comprising the two independent axles of a car-truck, a single motor disposed between and separately spring-supported upon said axles and provided with a suitable pinion upon its armature-shaft, and dynamometric gears on each axle, said gears being all in direct engagement with the armature-pinion. 50
2. An electric locomotive comprising a pair of independent axles to be driven, a motor extending between and separately spring-supported at or near the extremities of its field-magnet system upon each of said axles, and direct dynamometric spur-gearing between the armature-shaft of the motor and each of said axles. 55
3. In an electric locomotive, the combination of a motor having its armature centrally disposed between the independent axles of a railway-truck and provided with a suitable pinion and dynamometric gears, one on each axle, said gears engaging the pinion upon opposite sides, whereby said axles are each free to have a tilting movement independent of each other. 60
4. In an electric locomotive, the combination, with two axles of a truck, of a motor having its armature normally parallel with said axles and field-magnets extending from axle to axle, supporting-boxes sleeved upon the axles and connected with the ends of the field-magnet system of the motor, and springs above and below the boxes upon the axles, substantially as described. 65
5. An electric locomotive comprising two axles of a railway-truck, a motor having a double field-magnet, the outer ends of which extend around said axles, and having its armature and shaft centrally disposed between the axles and parallel therewith, spring-supports between the axles and the ends of the motor, and direct flexible gearing extending between the armature-shaft and said axles, substantially as described. 70
6. The combination, in an electric locomotive, of a motor spring-supported upon the truck, axles, flexible gear-wheels upon the axles, and a pinion upon the armature-shaft of the motor in mesh with the said gear-wheels, said pinion being formed of a plurality of toothed disks flexibly connected together and loosely secured upon the said shaft, so as to permit movement of the disks relatively to each other and to the teeth of the gears to be driven, substantially as described. 75
7. In an electric locomotive, a dynamometric gear-wheel comprising a hub rigid upon the axle to be driven, a rim having peripheral teeth, and radial springs extending between the hub and the rim, substantially as described. 80
8. The combination, with the two axles of a car-truck, of an electric-railway motor having a double field-magnet sustained part above and part below the axles to be driven, and means for supporting the upper and lower parts of the field-magnet independently. 85
9. An electric-railway motor formed of two horseshoe field-magnet cores, pole-pieces detachably secured to the ends of the cores, and magnetizing-coils upon the extremities of the pole-pieces, substantially as described. 90
10. The combination, with the axles of a car-truck, of a motor comprising a central armature and a double field-magnet extending over the said axles and divisible upon its central horizontal line, substantially as described. 95
11. The combination, with the axles of a car-truck, of a motor having a central armature parallel with and between the axles, a field-magnet extending over the said axles and horizontally divisible, spring-boxes sleeved upon the axles at each end of the motor, and detachable connections between the spring-boxes and the ends of the motor for spring-supporting the motor upon the axles, substantially as described. 100

In testimony whereof I affix my signature in presence of two witnesses.

Correction in Letters Patent No. 448,562.

It is hereby certified that in Letters Patent No. 448,562, granted March 17, 1891, upon the application of Charles J. Van Depoele, of Lynn, Massachusetts, for an improvement in "Electric Locomotives," an error appears in the printed specification requiring correction, as follows: In line 108, page 2, the word and numeral "Fig. 8" should read *Fig. 7*, and that the said Letters Patent should be read with this correction therein to make the same conform to the record of the case in the Patent Office.

Signed, countersigned, and sealed this 28th day of April, A. D. 1891.

[SEAL.]

CYRUS BÜSSEY,
Assistant Secretary of the Interior.

Countersigned:

C. E. MITCHELL,
Commissioner of Patents.
